UNITED STATES PATENT OFFICE

CLINTON DAVIDSON, OF SAN FRANCISCO, CALIFORNIA

CARBURETOR FOR INTERNAL COMBUSTION ENGINES

Application filed March 18, 1929. Serial No. 347,974.

My invention relates to engines of the internal combustion type and particularly to those engines wherein a relatively heavy liquid fuel is consumed. Engines of this character have been set forth in my copending applications, Serial No. 368,209, filed October 31, 1928, and Serial No. 330,819, filed January 7, 1929, which have since matured respectively into Patent No. 1,774,742 dated June 4, 1929, and Patent No. 1,759,187 dated May 20, 1930.

As I have also set forth in the aforementioned applications, it is the broad object of my invention to enable an internal combustion engine to be operated upon a relatively heavy hydrocarbon fuel while utilizing the well known Otto or Beau de Rochas cycle. Engines thus operated possess the light weight and cheapness of manufacture characteristic of the Otto cycle engine and are free from the restrictions normally placed upon them by the high quality of the fuel required to operate them.

Another object of my invention is to provide an Otto type engine in which the air supply is constant with respect to the rate of fuel supply for any one throttle setting under varying conditions of load and speed.

Another object of my invention is to provide an improved means for supplying fuel to an Otto type engine.

The invention possesses other advantageous features, some of which with the foregoing will be set forth at length in the following description where I shall outline in full that form of carburetor for an internal combustion engine of my invention, which I have selected for illustration in the drawing accompanying and forming part of the present specification. In said drawing, I have shown one form of carburetor for internal combustion engine embodying my invention, but it is to be understood that I do not limit myself to such form since the invention, as set forth in the claims, may be embodied in a plurality of forms.

In the drawing, to which I have made reference, Fig. 1 is a cross sectional view through the longitudinal axis of the device of my invention.

Fig. 2 is a cross section through the device of my invention along the line 2—2 of Fig. 1.

Fig. 3 is an end elevation of the device of my invention as indicated by the line 3—3 of Fig. 1.

Fig. 4 is a cross section through the device of my invention as indicated in the line 4—4 of Fig. 2.

In its preferred form, the internal combustion engine of my invention includes a manifold through which a quantity of air and atomized fuel flows, the flow of air and fuel being maintained substantially constant for any one setting of the throttle irrespective of the engine speed.

In the embodiment of the invention which I have chosen to disclose in the drawing, a manifold 6 is provided which is in communication with the cylinders of an Otto type engine. While this engine is not shown in the drawing it is preferably of the four stroke Otto cycle type and is proportioned and designed exactly like an engine of similar speed and power rating normally operated exclusively upon gasoline or a light hydrocarbon fuel.

An air conduit body 7 is provided in communication with the intake manifold 6 and is preferably maintained thereon by means of stud bolts 8. A fuel passage 9 is provided within the body 7 and is usually in communication with a suitable force pump capable of delivering a heavy fuel oil to the conduit under a substantially constant pressure which is sufficiently high to effect atomization of the oil upon its introduction into the atomizing means which I have indicated generally at 11. A gage connection 12 for indicating the oil pressure is also provided in communication with fuel passage 9.

To effect the atomization of the oil I have provided a nozzle 14, in communication with the fuel passage 9, having a minute orifice or aperture 16 therein from which the heavy fuel oil, usually of a gravity between 12° to 40° A. P. I., may be ejected directly into the intake manifold 6. The nozzle is preferably constructed as a separately machined plug screwed into the intake manifold side of the air conduit body. It is provided with the

oppositely tapered bores 17 and 18 to facilitate oil flow therethrough. A needle valve 19 projects into the nozzle 14 and co-operates with the nozzle bore 17 to provide orifices or apertures of varying extent depending upon the quantity of fuel which it is desired to eject from the nozzle.

A spirally threaded thimble 21 is preferably inserted into the nozzle 14 and closely overlies the needle valve 19 to impart a rapid helical motion to the flowing oil as it enters from the fuel passage 9. The needle valve is preferably adjustable with respect to the nozzle 14 by means of threaded portion 22 provided upon the lower portion of the needle valve and bushing 24 suitably retained in the air conduit body 7. The needle valve, which preferably projects for a considerable distance from extension 26 of the body 7, is sealed within the extension 26 by means of a packing gland 27 which prevents the passage of oil back along the needle valve.

The air conduit body 7 is expediently formed with a plurality of air inlet ports 31 through which enters the air admitted to the manifold. To effect a regulation of the quantity of air admitted to the manifold in relation to the quantity of fuel ejected through the nozzle I conveniently position within the air conduit 7 an air valve 32 which is maintained upon the needle valve by a sleeve 33 extending from the air valve. The air valve 32 is retained upon the needle valve by means of a set screw 34. Air valve 32 is likewise provided with a plurality of ports 36 which are positioned either to coincide with ports 31 in the air conduit or to be varied to admit only the desired lesser quantities of air to the intake manifold.

The lever arm 41, usually placed upon the extending end of the needle valve and retained thereon by means of the set screw 42, serves to accomplish the throttling of the fuel and air admitted to the manifold. A movement of the lever arm from one position to another causes the needle valve to move into the nozzle and reduces the quantity of fuel atomized. The movement of the lever arm also occasions the turning of the air valve to reduce the free area provided by the ports in the body 7 and in the air valve, thus reducing the air flow. Similarly, a movement of the lever arm in the opposite direction normally results in the entrance of more air and in the atomization of a greater quantity of fuel, the air valve being moved to provide a larger free area between the valve and the body and the needle valve being moved out of the nozzle to provide a larger aperture therethru.

I have found it desirable to provide a regulating system for controlling the quantity of air admitted to the intake manifold under varying conditions of engine speed and engine load. In the embodiment disclosed in the drawing I have preferably shown a piston

valve 51 positioned slidably within the air valve 32 and movable along the sleeve 33 of the air valve. A spring 53 is conveniently retained upon the sleeve 33 by means of the several lock nuts 54. The spring serves to bias the piston valve away from the intake manifold. To admit atmospheric pressure on one side of the piston valve the several ports 56 are provided in the valve 32.

In operation it is characteristic of the device of my invention that, upon an increase in engine speed with a constant throttle setting, any tendency for an increased amount of air to enter into the intake manifold is offset by the movement of the piston valve 51 towards the intake manifold in such a manner that the free area of the several air ports is decreased. The quantity of air admitted is thus kept substantially constant with respect to the quantity of fuel ejected from the nozzle and the tendency to supply a lean mixture to the carburetor is overcome. Likewise, when the engine is operating with a constant throttle setting at a high speed and under an increasing load, the piston will move away from the intake manifold as the speed decreases to permit the entrance of a relatively constant quantity of air. The air drawn into the manifold is thus maintained substantially constant, for any one position of the needle valve and the air valve, irrespective of the speed of the engine.

I claim:

1. A carburetor comprising a body having an unobstructed induction passage therein, a fuel nozzle in said passage, a valve for controlling said nozzle, a valve for controlling air flow through said passage, means for mechanically moving said valves in unison in both directions between their extreme positions, and means responsive to pressure in said passage for additionally controlling air flow through said passage.

2. A carburetor comprising a cylindrical body bounding an induction passage, said body having air inlet apertures therein, a fuel nozzle in said passage, a valve for controlling said nozzle, a cylindrical valve in said body, said valve having ports adapted to register with said apertures for controlling air flow into said passage, means for moving said valves simultaneously, and a piston valve movable in accordance with pressure in said passage and adapted to overlie said apertures to control air flow therethrough.

3. A carburetor comprising a body having air inlet apertures and an induction passage therein, a fuel nozzle in said passage, a valve cooperating with said nozzle, a valve for controlling air flow through said apertures; each of said valves being adapted to be moved between two extreme positions thereof, mechanical means for moving said valves in unison in both directions between said positions

for controlling simultaneously fuel flow through said nozzle and air flow through said apertures, and means responsive to pressure in said passage for additionally controlling air flow through said apertures.

In testimony whereof, I have hereunto set my hand.

CLINTON DAVIDSON.
